UNITED STATES PATENT OFFICE.

EDWARD L. McCCLAIN, OF GREENFIELD, OHIO.

HORSE-PAD.

1,119,094.

Specification of Letters Patent.

Patented Dec. 1, 1914.

Original application filed April 25, 1912, Serial No. 693,242. Divided and this application filed September 6, 1913. Serial No. 788,423.

To all whom it may concern:

Be it known that I, EDWARD L. McCCLAIN, a citizen of the United States of America, and resident of Greenfield, county of Highland, and State of Ohio, have invented certain new and useful Improvements in Horse-Pads, of which the following is a specification.

This application is a division of an application for United States Letters Patent, filed by me upon April 25th, 1912, and serially numbered 693,242, for "means for securing horse pads in place".

The object of the invention is a horse pad, in which the hook and the fastener therefor are of a shape, such, and are so combined with the pad, as to protect the covering of the pad from cutting or tearing action of the fastener. This object is attained by the means described in the specification and illustrated in the accompanying drawings, in which,

Figure 1 is a perspective view of a horse pad embodying my invention, and of a horse collar, showing the position of the pad in relation to the latter in use. Fig. 2 is an enlarged sectional view, taken upon line 2—2 of Fig. 1. Fig. 3 is a sectional view, taken upon line 3—3 of Fig. 2. Fig. 4 is a detail rear elevation of a section of a pad embodying my invention.

The hook is secured to the pad by means of a staple. The staple is so combined with the pad and the hook, that the continuous and rounded portions of the staple contact with the pad, and the broken and roughened parts thereof are housed by a portion of the hook, so as to prevent the staple cutting the covering of the pad. Hook A consists of a ring-shaped strip of metal having parallel edges, and has near one of its ends a small cylindrical portion *a*, which forms a journal loop for journaling it upon staples and for housing the broken and roughened ends of the staples. The back B of the staple contacts with the inner cover of the pad and is substantially parallel to the edge *d* of the pad D. The prongs *b* *b'* of the staple stand at a distance apart equal to the width of the strip of metal forming the hook, and project through the pad, ad-

jacent to the opposite ends of the journal loop, and the ends thereof are bent over within the journal loop of the hook.

In use, since the back of the staple has a 55 broad bearing upon the inner cover of the pad, and has no broken edges in contact therewith, the pull upon the hook is evenly distributed over the cover, and there is consequently no cutting action of the back of 60 the hook upon the inner cover. Since the prongs contact with the ends of the journal loop and the ends of the prongs are housed by the journal loop, they have no opportunity of cutting the outer covering of the 65 pad. This relative position of the staple and the hook likewise holds the hook from sliding longitudinally of the pad.

What I claim is:

1. The combination of a horse pad, a hook 70 having a cylindrical journal loop contacting with the outer surface of the pad, and a staple whose back contacts with the inner surface of the pad and whose prongs project through the pad and are bent inward 75 into the journal loop.

2. The combination of a horse pad, a hook having a journal loop at one end contacting with the pad, and a staple whose prongs are spaced apart a distance equal to the width 80 of the journal loop, whose back contacts with the inner surface of the pad, and whose prongs project through the pad upon opposite sides of the journal loop and are turned inward within the journal loop. 85

3. The combination of a horse pad, a hook and a staple, the hook consisting of a ring-shaped strip of metal having at one end a cylindrical journal loop contacting with the pad, and the staple being U-shaped, of a 90 span equal to the width of the journal loop and having its back contacting with the pad and its prongs projecting through the pad upon opposite ends of and bent down into the journal loop. 95

In testimony whereof, I have hereunto subscribed my name this third day of September, 1913.

EDWARD L. McCCLAIN.
